UNITED STATES PATENT OFFICE.

FERDINAND SCHAR, OF SCHWECHAT, NEAR VIENNA, AND RUDOLF THEUMER, OF VIENNA, AUSTRIA.

GAS BURNER.

Application filed November 30, 1923, Serial No. 677,674, and in Austria December 15, 1922.

This invention relates to gas burners of the type wherein an automatic cut-off of the gas flow is accomplished whenever the burner goes out.

5 One important object of the invention is to provide a novel, economically constructed and improved gas burner of this type.

A second important object of the invention is to provide a gas burner wherein the 10 controlling valve will be held open so long as the burner is alight.

With the above and other objects in view as will be hereinafter apparent, the invention consists in general of certain novel details of construction and combinations of parts hereinafter fully described, illustrated 15 in the accompanying drawings and specifically claimed.

In the accompanying drawings like characters of reference indicate like parts in the several views; and:

Figure 1 is a longitudinal median vertical section through a gas burner constructed in accordance with this invention.

25 Figure 2 is a bottom plan view thereof partly in section.

In the present construction of the burner there is provided a tubular body 10 which has at one end an air passage 11 and into this 30 tubular member extends a nipple 12 which is axially arranged with respect to the tubular member 10. In the top of the tube 10 is provided a slot 13 wherein moves a valve support 14 which carries a valve stem 15 provided on one end with a valve 16 of the needle valve type and arranged to close the opening in the nipple 12. The shank or stem 15 is gripped by the member 14 and the latter depends from a slide 17 which is 40 actuated by a lever 18 provided with a thumb-piece 19, the lever normally being retracted by a spring 20.

At the other end of the apparatus there is provided a burner 21 having gas holes 22 therein. Extending forwardly of the burner 21 is a pair of fixed jaws 23 one of which has a spring pressed member 24 projecting there-through. Underneath the burner is provided a by-pass 25 having an opening 26 which is located just beneath a bridge 27 extending between the grips 28 of a horse shoe shaped member 29. This member 29 receives the upper end of the stem 15 as indicated at 30.

55 In operation it may be supposed that the

valve is closed. Upon depressing the thumb-piece 19 the slide moves forwardly and the valve opens. Then a mixture of air and gas passes through the member 10. Part of this mixture flows through the openings 22 and 60 may be lit. Another part flows through the opening 26 and heats the bridge 27. Consequently this bridge expands, forces the grips 28 outwardly so that they seize the members 23 and thereby hold the valve 16 65 away from its opening, even though the spring 20 urges it backwardly. In addition, in order to prevent too much closing of the jaws or grips 28 there is provided a prong 31 which extends from one grip toward the 70 other.

There has thus been provided a simple and efficient device of the kind described and for the purpose specified.

It is obvious that minor changes may be 75 made in the form and construction of the invention without departing from the material spirit thereof. It is not, therefore, desired to confine the invention to the exact form herein shown and described, but it is desired 80 to include all such as properly come within the scope claimed.

Having thus described the invention, what is claimed as new is:

1. In combination, a gas burner having a 85 gas inlet, a shutting-off member to control admission of gas to the burner and a thermostatic locking device located near the burner flame and including a rigid locking member to hold the shutting-off member in 90 its open position and a resiliently supported lock pin attached to the said rigid locking member.

2. In combination, a gas burner having a 95 gas inlet, a valve movable toward and from said inlet to control admission of gas to the burners, a stem carrying said valve, a pair of fixed jaws, a U-shaped head member having arms constituting grips and slidably between said jaws, said head member being 100 connected to the valve stem at the end remote from the valve, a bridge piece connecting the arms of the U-shaped member, and a branch leading from said burner and terminating beneath the bridge piece. 105

3. In combination, a gas burner having a gas inlet, a valve movable toward and from said inlet to control admission of gas to the burners, a stem carrying said valve, a pair of fixed jaws, a U-shaped head member hav- 110

- ing arms constituting grips and slidable between said jaws, said head member being connected to the stem at the end remote from the valve, a bridge piece connecting the 5 arms of the U-shaped member, a branch leading from said burner and terminating beneath the bridge piece, and yieldable means carried by one of said jaws against which one of the grips engages.
- 10 4. In combination, a gas burner having a gas inlet, a valve movable toward and from said inlet to control admission of gas to the burners, a stem carrying said valve, a pair of fixed jaws, a U-shaped head member having arms constituting grips and slidable between said jaws, said head member being connected to the stem at the end remote from the valve, a bridge piece connecting the arms of the U-shaped member, a branch leading 15 from said burner and terminating beneath the bridge piece, yieldable means carried by one of said jaws against which one of the grips engages, and means to limit the inward movement of the grips with respect to 20 each other.
5. In combination, a gas burner having a gas inlet, a valve movable toward and from said inlet to control admission of gas to the burners, a stem carrying said valve, a pair of fixed jaws, a U-shaped head member having arms constituting grips and slidable between said jaws, said head member being connected to the stem at the end remote from the valve, a bridge piece connecting the 25 arms of the U-shaped member, a branch leading from said burner and terminating
- beneath the bridge piece, yieldable means carried by one of said jaws against which one of the grips engages, means to limit the inward movement of the grips with respect to each other, and manual means for 40 operating said valve.
6. In combination, a gas burner having a gas inlet, a valve movable toward and from said inlet to control admission of gas to the burners, a stem carrying said valve, a pair of fixed jaws, a U-shaped head member having arms constituting grips and slidable between said jaws, said head member being connected to the stem at the end remote from the valve, a bridge piece connecting the arms of the U-shaped member, a branch leading from said burner and terminating beneath the bridge piece, yieldable means carried by one of said jaws against which one of the grips engages, means to limit the inward movement of the grips with respect to each other, and manual means for operating said valve, including a support for said stem adjacent the valve provided end, said burner having a slot through which the said support passes, a slide on said burner carrying said support and having an upward projection, a bell crank lever having one arm engaging said projection and the other arm constituting a finger piece, and a spring engaging said lever to move it in a direction to cause the valve to open. 45 50 55 60 65
- In testimony whereof we affix our signatures.

FERDINAND SCHAR.
ING. RUDOLF THEUMER.
